UNITED STATES PATENT OFFICE.

EDWARD C. MCKENZIE-MARTYN, OF SHORT HILLS, NEW JERSEY, ASSIGNOR TO STANDARD OIL DEVELOPMENT COMPANY, A CORPORATION OF DELAWARE.

PROTECTIVE DEVICE.

Application filed April 17, 1922. Serial No. 553,701.

My invention relates to valves and protective devices, used on systems and receptacles containing fluids and particularly where there is more or less corrosive action. The 5 features and utilities of the invention will be clearly understood as the description proceeds, reference being had to the accompanying drawings, in which—

Fig. 1 is a vertical section of an embodiment of my invention;

Fig. 2 is a similar view showing the relation of assemblage;

Fig. 3 is a perspective detail of a guard grid;

Fig. 4 is a vertical section showing a detail of a modified form of protective device, and

Fig. 5 is a similar view showing further modifications and assemblage.

The numeral 1 designates a container in which there is fluid and while my invention is applicable over a considerable range, including not only simple systems and receptacles, but also special apparatus in which 25 chemical vapors and gases are contained at low temperatures, also heated apparatus such as steam boilers, autoclaves, digesters, vulcanizers, chemical stills, etc., by way of example the invention will be described as applied to an oil still, as this well exemplifies an extreme case, in which vapors which are corrosive, hot, and under pressure have to be reckoned with. In some of the more recently used petroleums, sulfur compounds are 35 present in considerable amount and these under still conditions form vaporous constituents which exercise a corrosive action such as to damage safety valves of the usual types. Continued exposure on the still side 40 results in corrosion along the valve disc and seat such as either to produce leaks, or what is worse, cause sticking.

In the drawing, since the construction of the still itself is no part of my invention, for 45 simplification only a sufficient portion of the upper wall thereof is shown to make clear the relationship of my invention. Connected to the still is a safety valve A (see Fig. 2), the detail construction of which may be conventionally represented as comprising a 50 valve-disc 2 on a stem 3 slidably in the yoke 4 and held at a predetermined pressure by a spring 5. Joining the valve and the still is a housing 6 fastened to the respective flanges 55 by suitable means, such as bolts 6'. The

housing provides a frame-seating for a protective septum 7 clamped tightly in place by suitable clamping means 8, and made of non-corrosive or slightly corrosive material, such as Monel metal or aluminum. The 60 thickness of the septum is so gaged that it will rupture at about the predetermined pressure for which the safety valve is set, or the septum may be made rather thick and be suitably scored to break out. It is thus seen 65 that the valve surfaces are normally shielded against corrosive action and yet, through rupture of the septum at the predetermined pressure the functioning of the safety valve is in no wise interfered with.

In the use of such septa it occasionally is necessary to get at the septum for inspection, or for renewal when the valve has blown, and if this be accomplished by demounting the valve, serious loss of time results, also difficulties in always securing tight joints. To meet this, I have particularly provided for ready access. In the form illustrated in the drawings this comprises cover plates 9, detachably held by fastening means such as 70 screws 10. Such covers may be positioned as desired, so as to afford access; a double set, fore and aft as shown being particularly useful, however a cover on the still side must be gasketed tightly against leaks, while a cover 75 aft need not be so carefully tight.

To prevent pieces of a broken septum from jamming in the valve seat I provide a catcher or guard grid 11. This may be of any suitable form, from cast metal to heavy wire 80 mesh, however the simple stamping as shown, is advantageous as the flange 12 provides a convenient holding means, being simply clamped under the cover plate.

In some instances it is desirable to use a 85 plurality of septa, as shown in Fig. 2, since with some materials there is a slight variation in the yield point for septa similarly prepared, and with more than one available, more accurate release at the pressure desired 100 is secured.

In the modifications shown in Figs. 4 and 5 of the drawings, the septum 7 is made more fragile, not being intended to carry any pressure load, and is backed up by a close fitting 105 follower 13 whose stem 14 is slidably mounted in the cover plate 9 and is held in position by a break-pin 15, the pin being made of material of known coefficient so as to shear at a predetermined pressure. Preferably the 110

break-pin is placed through a slidable block 16 (see Fig. 4) in a cap 17 mounted on the boss projection of cover plate 9 by suitable means, such as screw threading, so as to abut against the stem 14 when in position. This construction makes possible the use of already charged mounts of break-pins; after a blow-out it being merely necessary to renew the septum and remove the cap 17 with the sheared pin and substitute another cap carrying a block 16 and new pin, the operation requiring but a few moments time.

If desired, the break-pin may more simply be placed directly through a boss enlargement 18 of the cover plate 9 as shown in the lower mounting in Fig. 5, or advantageously a cap or casing 18 may be placed over the plunger stem and filled with oil to lubricate and to act as a dash-pot, the oil displaced finding exit 20 by any convenient arrangement, as for instance escape duct 19 along the stem into the housing.

In the modifications shown in Figs. 4 and 5, a weighted safety valve or any other desired type may be mounted above the housing 6, the throatway of the valve below the disc being indicated at A', Fig. 5, the further detail of such valve being immaterial here. However for some uses I contemplate omitting the standard safety valve and in such cases my septum and special mounting make a very reliable safety valve of itself as the factor of corrosion-damage is eliminated and by use

of the proper break-out element the desired pressure limit set is readily attained.

While I have described my invention with reference to certain details of embodiment, it is to be understood that this is illustrative, and not limitative, and the invention is to be regarded as limited only by the claims below.

What I claim is:

1. In a device of the character described, the combination of a pressure fluid-holding apparatus, a plurality of protective septa, a housing for said septa, and a removable cover 45 affording access to the septa without disturbing the connection of the housing to the apparatus.

2. In a device of the character described, the combination of a protective septum, a backing plunger, a break-pin for supporting said backing plunger, and a detachable cap at the rear of the plunger.

3. In a device of the character described, the combination of a protective septum, a backing plunger, a break-pin for supporting said backing plunger, a detachable cap at the rear of the plunger, and an outlet duct connecting with the cap.

4. In a device of the character described, the combination of a protective septum, a backing plunger, a detachable cap at the rear of the plunger, and a break-pin within said cap.

EDWARD C. MCKENZIE-MARTYN.
